HOT-AIR DRIER.

1,185,899.

Specification of Letters Patent.

Patented June 6, 1916.

Application filed August 10, 1912. Serial No. 714,364.

To all whom it may concern:

Be it known that I, CHARLES E. GEIGER, a citizen of the United States, residing at Louisville, in the county of Jefferson and 5 State of Kentucky, have invented certain new and useful Improvements in Hot-Air Driers, of which the following is a specification.

This invention relates to driers, and more 10 particularly to the class designated as rotary driers, and the principal object of this invention is to provide an apparatus of the class described in which the heating is obtained directly from a furnace, a part of 15 the drier being rotatable in the firebox, and the heat arising therefrom being deflected and directed through suitable tubes through the drier so that the greatest drying effect may be obtained and an effective 20 and efficient apparatus result.

A further object of the invention is to provide means for inducing a circulation of the heated gases through the drier.

For the attainment of these ends and the 25 accomplishment of other new and useful objects, as will appear, the invention consists in the features of novelty in the construction, combination and arrangement of the several parts generally shown in the 30 accompanying drawings and described in the specification, but more particularly pointed out in the appended claims.

In the drawings, Figure 1 is a longitudinal sectional view of a drier constructed in 35 accordance with the principles of my invention; Fig. 2 is a plan view of the same; Fig. 3 is a longitudinal sectional view of a modified form of drier, embodying the principles of my invention; Fig. 4 is a detail view 40 showing the construction of one of the rotatable cylinders; Fig. 5 is a detail view showing the method of spacing the tubes from the wall of the cylinder; and Fig. 6 is a detail view of the connecting plate between 45 the cylinders.

In rotary driers it is customary to employ steam as the heating element and to utilize the steam for this purpose it is necessary to provide an expensive structure which prevents the escape of steam, and with such a structure it is necessary also to employ a boiler for furnishing the steam.

The present invention consists of an apparatus which utilizes the heated air and gases 55 which arise from a furnace for drying the

material, and in order to insure that the heated gases will be directed in the proper direction artificial means is employed for forcing the said gases through the drying cylinders in the desired manner.

Referring now more particularly to the drawings and in the present exemplification of the invention the numeral 8 is employed generally to designate a firebox, of any desired or suitable construction, in which the 60 grates 9 are disposed. These grates may be of any suitable well known construction, and a feed box 10 is commonly employed in connection therewith, so that fuel may be fed upon the grates from without the firebox. At the top of the fire box is disposed a stack or chimney 11, provided with a damper 12, which may be moved and set in any desired position.

Extending into the fire box on one side 75 thereof is a rotatable cylindrical shell 13, which is suitably mounted for rotation upon the supports 14, preferably adjacent the ends thereof. At the end which is inserted in the side of the firebox 8 there is disposed 80 a circular plate 15 extending around the inside edge thereof, which is provided with a number of perforations into which the ends of tubular members 16 are inserted. Extending through the fire box 8 and having contact at one end with the inside edge of the plate 15 is a cylindrical member 17, the other end being rotatably mounted upon a suitable support 18. These cylinders 17 and 13 are preferably connected together 85 and are supported so that they may be freely rotated. Any suitable driving mechanism may be employed, such for example, as that illustrated by the drawing, from which it will be seen that the cylindrical 90 member 13 is provided with an outer gear 19 mounted upon a shaft 20. This shaft is connected by means of bevel gears 21 and a driving shaft 22 to a driving pulley 23 mounted thereon.

At the free end of the cylinder 17 is disposed a yoke 24 which extends within a feeding hopper 25. This feeding hopper is suitably mounted upon standards 26 and is provided with a conveyer 27, preferably of the type known as a spiral conveyer, which may be operated in any well known manner, as for example, by means of chains and gearing connecting it with the rotating cylinders. This hopper 25 may be fed in any 110

desired or suitable manner, as, for example, through a door 28 in the top thereof. At the free end of the cylinder 13, it is provided with a housing 29, in the bottom of which a spiral conveyer 30 is disposed which is operated by a gear connection with the cylinder. The housing 29 is fixed with respect to the cylinder, and the cylinder rotates freely within the housing. The joints 10 made between the housing and the cylinders, as well as the joints made between the cylinders and the firebox, are as nearly air tight as it is feasible to make them, but, of course, need not be absolutely air tight, the 15 object being merely to prevent the leakage of the heated gases as much as possible.

It will be seen that the tubes 16 are disposed within the cylinder 13 at the outer edge thereof, and that they communicate 20 with the firebox at one end around the outside of the cylinder 17, and at the other end they preferably extend, as shown in Figs. 1 and 2, beyond the ends of the cylinder 13. These tubes 16 are preferably spaced from 25 the walls of the cylinder 13 in any desired or suitable manner, such, for example, as that shown in detail by Fig. 5, from which it will be seen that a member 31, preferably in the form of an angle iron, is secured to 30 the inclined face of the cylinder, with one arm thereof extending in a position to abut one of the tubes 16 and to hold it in a spaced position with respect to the wall of the cylinder. This permits the material to be dried 35 to fall between two adjacent tubes as the cylinder rotates so that nearly the entire surface of the tubes may be utilized for heating purposes.

In order to produce sufficient draft through 40 the drier and to insure that the draft will be properly directed a fan or blower 32 is employed. This blower is provided with a tubular connection 33, which is connected to the hopper 25, preferably in the top 45 thereof, and which has a discharge stack or tube 34.

Disposed in the cylindrical portion 17 are 50 a plurality of flights 35, which are preferably inclined slightly to the longitudinal axis of the cylinder so that as the cylinder rotates the material contained therein will be directed continuously in a forward direction. These flights 35 are shown more 55 clearly in Fig. 4, and may be formed with the extending portion perpendicular to the inclined face of the cylinder 17, or at a slight inclination thereto; preferably the different forms of flights are arranged alternately with respect to each other, as shown 60 in Fig. 4.

In operation the cylinders 13 and 17 are rotated and the material to be dried is fed into the cylinder 17 through the hopper 25, from which it advances into the cylinder 13 by the continued rotation of the cylinders.

The fire is placed on the grates in the fire box, and the damper 12 may be turned to open the stack when desired, as for example, in starting or replenishing the fuel. When the damper 12 is closed, the heated gases in 70 the fire box are directed through the tubes 16 and into the housing 29 at the end thereof. The fan or blower draws the air and gases from within the cylinders and from the housing 29 through the cylinders so that 75 a draft is created from the fire box through the tubes 16, housing 29, through the cylinders 13 and 17, through the hopper 25, pipe 33 and through the blower 32 out through the stack 34. The cylinder 17 being disposed 80 within the fire box receives the heat directly so that the material containing the greatest amount of moisture is subjected to the greatest heating effect, and since the gases and air are drawn off at this end, the moisture and 85 gases arising from the material to be dried will not pass over the material which does not contain so much moisture. In other words, the material containing most moisture 90 is nearest the vapor discharge end.

If desired, the fan or blower instead of being disposed at the end adjacent the feed-ing hopper may be positioned at the other end, as shown more clearly in Fig. 3. With 95 this construction it is necessary to alter the form of the housing at the discharge end. This housing 36 is formed with an extending portion 37 at the end thereof, and a tubular portion 38 extends through the projection into the end of the cylinder 13. Inside of the housing is a manifold 36' spaced 100 from the end of the cylinder 13, into which the ends of the tubes 16 are connected, the manifold being formed with a portion 36^a 105 which extends within the said extending portion 37 of the housing 36. Connected with the extending portion 37 is a pipe 39 and connected with the tubular portion 38 is a pipe 40, which form the admission and 110 discharge pipes for the fan or blower 32. The blower is suitably supported upon a frame or the standards 41.

In the exemplification of the invention shown by Fig. 3 the firebox 8 is longer than 115 that shown by Figs. 1 and 2, and the cylinder 42, corresponding to the cylinder 17, is also longer having a portion thereof formed with the flights 35 and another portion which is disposed directly over the grates 9 120 free from said flights or projections. In this portion, however, there are disposed a number of metallic bodies 43, which may be of any desired shape or material, but which are preferably in the form of metallic balls, 125 the purpose of which is to break up chunks of the material to be dried and to prevent the material from forming in lumps and compact masses, the cylinder as it rotates causing the bodies 43 to be tumbled about in the cylinder so that the material to be dried

is broken up thereby. To prevent the said bodies from being displaced in the cylinder the inside ribs 44 are provided, which hold the bodies in their longitudinal position.

5 6 The operation of a drier of this form is similar to that already described and no further description is deemed necessary.

It is obvious that the blower may be disposed at either end of the drier, as shown in 10 the drawings, its operation being the same in either position. When the blower is positioned at the discharging end of the drier it is necessary to provide a discharge stack 45 at the other end of the drier, preferably 15 extending from the top of the feeding hopper 25.

While I have thus described the preferred embodiment of my invention, it is obvious that others skilled in the art to which said 20 invention appertains may make various changes in the construction, combination and arrangement of the several parts, without departing from the spirit and scope of my invention.

25 7. What I claim is:

1. A hot air drier comprising a furnace, a single rotatable cylinder with pipes therein for receiving hot air from the furnace having a portion extending directly through 30 the furnace, and means to draw hot air from the pipes through the cylinder.

2. In a hot air drier a furnace, a single rotatable cylinder having a portion extending through the furnace with pipes therein 35 connecting with the furnace and extending to one end of the cylinder, and draft-inducing means to cause the hot air from the pipes at the end of the cylinder to be passed through the cylinder.

40 3. In a hot air drier, a furnace, a cylinder rotatable in the furnace with pipes extending from an intermediate point to one end of the cylinder within the cylinder but having communication with the furnace, and 45 means to cause the hot air from the pipes at the end of the cylinder to be passed through the cylinder.

4. In a hot air drier, a furnace, a rotatable cylinder of which a part is within the furnace to receive the direct heat therefrom, and pipes within the other portion of the cylinder communicating with the furnace and extending to the end of the cylinder outside of the furnace, and means to cause the 55 hot air from the furnace to pass therefrom through the pipes to the end of the cylinder and thence to return through the cylinder.

5. In a hot air drier, a furnace, a rotatable cylinder having an enlarged portion with 60 pipes therein communicating with the furnace, and means to cause hot air to pass through the pipes to the end of the cylinder and thence through the cylinder from end to end.

65 6. In a hot air drier, the combination with

a furnace, of a rotatable cylinder having an enlarged portion at one end with tubes therein communicating with the furnace and extending to the end of the cylinder, the smaller part only of the cylinder being within 70 the furnace, and means for causing the hot gases from the furnace to pass first through the pipes to the end of the cylinder and then in a reverse direction through the cylinder from end to end.

75 7. In a drier of the class described, the combination with a furnace, of a cylinder with a portion directly rotatable therein having draft pipes communicating with the furnace at an intermediate point along the 80 cylinder and extending to one end thereof, means for causing the draft from the furnace to pass first through the pipes to the end of the cylinder and thence through the cylinder from end to end, and means for 85 feeding material to be dried at one end of the cylinder.

8. In a drier of the class described, the combination with a furnace, of a cylinder having a portion of reduced size rotatable in 90 the furnace, the other portion of the cylinder having pipes extending from the furnace to the end of the cylinder, means for feeding material to be dried to the cylinder at the smaller end and for removing it at 95 the other end, and draft-inducing means for causing the hot air from the furnace to be drawn through the pipes to the end of the cylinder and thence returned through the cylinder in the opposite direction.

100 9. In a drier of the class described, the combination with two cylindrical portions, one larger than the other placed end to end, a perforated plate disposed between the adjacent ends of the said members, and tubes 105 disposed in the larger cylinder with their ends secured in the perforations in said plate.

10. In a drier of the class described, the combination with two cylindrical portions, one larger than the other placed end to end, a perforated plate disposed between the adjacent ends of the said members, tubes disposed in the larger cylinder with their ends secured in the perforations in said plate, 110 and means secured to the inside of the larger cylinder for holding the tubes at a spaced distance therefrom.

11. In a drier of the class described, the combination with a furnace having a fire chamber, of a rotatable cylinder disposed therein with one end protruding through the inside of the fire chamber, the opposite end of the fire chamber being provided with an opening, a second cylindrical member larger than the first named member disposed in said opening with the end thereof surrounding the end of the first named cylindrical member, a perforated plate forming connection between the two cylindrical members, 115 120 125 130

4
tubes disposed in the larger cylindrical member and extending through the perforations in said plate, and means producing a suction through the said tubes from the fire chamber and through both of said cylindrical members.

12. In a drier of the class described, the combination with two cylindrical members, one larger than the other, and placed end to end, of a perforated plate disposed between the adjacent ends of said members, tubes mounted in a larger member with their ends secured in said perforations, a closed housing in the free end of the larger member, a furnace having a fire chamber in which the smaller cylindrical member is disposed with the tubes of the larger member communicating with the interior of the fire chamber, the free end of the smaller member extending beyond the furnace, means to feed material to be dried at the free end of the smaller cylinder, a draft producing device operative to produce a draft from the fire chamber through the tubes in the larger cylinder in one direction and through both of the cylindrical members in the opposite direction.

13. In a device of the class described, the

combination with two cylindrical members, one larger than the other, and placed end to end, of a perforated plate for connecting the adjacent ends, tubes disposed in the larger cylinder and secured in the perforations in said plate, means to rotate the cylinders, a device for feeding material to be dried to the smaller cylinder, a housing at the free end of the larger cylinder, a conveyer disposed in said housing for discharging the dried material, a furnace having a fire chamber surrounding the smaller cylinder and forming communication with the tubes in said larger cylinder, and means to produce a continuous draft from the fire chamber through the tubes in one direction and through both cylindrical members in the opposite direction.

45
In testimony whereof I have signed my name to this specification, in the presence of two subscribing witnesses, on this eighth day of August, A. D. 1912.

CHARLES E. GEIGER.
